Application filed December 19, 1901. Serial No. 86,616. Term of patent 7 years.

To all whom it may concern:

Be it known that I, WILLIAM W. BROMHAM, a citizen of the United States, and a resident of the city of New York, borough of Manhattan, in the county and State of New York, have invented and produced a new and original Design for a Brush or Mirror Back, of which the following is a specification, reference being had to the accompanying drawing, forming a part thereof, in which the figure is a face view of a brush-back, showing my design.

The invention relates to toilet articles, such as brushes and hand-mirrors.

The design in its entirety consists of the body A, terminating in the handle B and appearing with an approximately-oval-shaped convex center C, surrounded by a border in relief and composed of symmetrically-arranged poppy-flowers D, leaves E, and scrolls

F, the handle C also appearing near its end, ²⁰ with a poppy-flower D', leaves E', and scrolls F', the contour of the body and handle appearing in undulating lines.

The leading feature of the design consists of the poppy-flowers and ornamentation. ²⁵

Having thus described my invention, I claim as new and desire to secure by Letters Patent—

The design for a brush or mirror back, as herein shown and described. ³⁰

In testimony whereof I have signed my name to this specification in the presence of two subscribing witnesses.
